ETCHING MACHINE

Joseph Strauss, Hopewell, N.J., assignor to Trenton Times Corporation, Trenton, N.J., a corporation of Delaware
Original application Feb. 6, 1957, Ser. No. 638,509.
Divided and this application Apr. 22, 1958, Ser. No. 730,209

8 Claims. (Cl. 41—9)

The present invention relates to a new and novel etching machine, and more particularly to an etching machine utilized in connection with printing plates or the like.

The present application is a division of U.S. patent application Serial No. 638,509, filed February 6, 1957.

The present invention is especially adapted for use in etching magnesium plates as one step in the processing thereof as, for example, described in the method disclosed in my aforementioned copending application. Etching operations on printing plates are often a critical matter since the depth of the etches is very important to achieve the desired results. Accordingly, etching operations ordinarily required a very skilled operator in order to achieve the proper degree of etch. It is a primary concern of the present invention to provide an apparatus which may be quickly and easily adjusted, and is fully automatic in operation whereby the skill required of an operator is reduced to a minimum.

Numerous prior art devices have been constructed for performing etching operations, and one of the problems which has been encountered is the fact that the etching fluid has a tendency to become concentrated in certain areas thereof greater than other areas thereby causing an uneven etch to be made. It is conventional practice in etching machines of this type to raise and lower paddle assemblies within the machine to control the distribution or spray of the etching fluid. This, of course, requires a rather complex and bulky arrangement which is awkward to operate.

The new and novel structure, according to the present invention, incorporates a pumping system which is employed to distribute the etching fluid from a reservoir supply to a plurality of troughs from whence the etching fluid is distributed to the printing plates by the paddle assemblies. The pumping system distributes the etching fluid from the reservoir to the troughs, thereby effecting a continuous agitation and mixing of the etching fluid to prevent concentrations of weak etching fluid. Rather than providing adjustable paddle assemblies as is common in the prior art, the pumping system is so employed for controlling the level of the etching fluid within the troughs of the device so that the amount of etchant distributed by the paddle assemblies is thereby controlled without necessitating any movement of the paddle assemblies. Easily accessible controls are provided on the exterior of the machine whereby an unskilled operator may make a few simple adjustments and accurately control the etching operation. The controls are so connected that an operator may actuate the paddle assemblies either conjointly or either paddle assembly may be operated separately.

An object of the present invention is to provide a new and novel etching machine which may be quickly and easily operated and which minimizes the skill required of an operator.

Another object of the present invention is to provide an etching machine which substantially eliminates concentrations of weak etching fluid.

A further object of the present invention is to provide an etching machine wherein the distribution of etchant may be easily controlled, and the paddle assemblies of the machine may be individually operated.

Yet another object of the present invention is to pro-

2

vide an etching machine which is simple and inexpensive in construction, yet which is efficient and reliable in operation.

A still further object of the present invention is to provide an etching machine wherein the etchant fluid is distributed uniformly against the face of a plate disposed within the machine.

Other objects and many of the attendant advantages of the invention will become more apparent when considered in connection with the accompanying specification and drawings wherein:

FIG. 1 is a perspective view of the etching machine with portions thereof being broken away to illustrate the principle of operation;

FIG. 2 is an enlarged sectional view illustrating the plate rotating means embodied in the etching machine;

FIG. 3 is a sectional view taken along line 3—3 of FIG. 2, looking in the direction of the arrows;

FIG. 4 is a front elevational view of the assembly shown in FIG. 2;

FIG. 5 is a transverse sectional view through the etching machine illustrating the cover construction and details of the exhaust ducting system;

FIG. 6 is a transverse sectional view taken through one of the paddle assemblies;

FIG. 7 is an elevational view showing an end portion of one of the paddle assemblies;

FIG. 8 is an elevational view illustrating the mounting assembly of one of the paddle shafts; and

FIG. 9 is a partial perspective view of an end portion of one of the deflecting boards and illustrating adjustable mounting means associated therewith.

Referring now more particularly to the drawings wherein like reference characters designate corresponding parts throughout the several views, the etching machine is shown most clearly in FIG. 1 and is constructed of generally rectangular form and is provided with a vertical rear wall 278 and a front wall 279 spaced therefrom with side walls 280 interconnecting the front and rear walls as well as a bottom wall 281 so as to form an enclosure within which a plate 282 is disposed during the etching process. On the inside of the tank and along the bottom thereof is provided an open top trough 283 and a similar trough 284 is disposed in spaced parallelism thereto as is shown most clearly in FIG. 1. Each of these troughs extends completely in between the side walls of the machine and associated with each of these troughs is a paddle assembly, the ends of which are shown in FIG. 1 and designated by the reference characters 285 and 286.

Each paddle assembly incorporates a plurality of splashing blades which dip into a supply of etching solution received in the respective tanks 283 and 284 and when rotated, splash or spray the etching solution forwardly to distribute it more or less evenly against the face of the plate 282 disposed within the machine. The tanks 283 and 284 are connected directly to the rear wall 278 of the machine and the paddle assemblies 285 and 286 are journaled in the side walls 280, as will be more fully described hereinafter. With the particular arrangement shown, there are actually three supplies of etching fluid within the interior of the machine. The first supply, which is actually a reservoir, is contained in the bottom portion of the machine forwardly of the lower trough assembly 283 and the level of such supply will, at no time, except the height of the trough 283 so that there is no communication therebetween. The other two supplies are contained within the troughs 283 and 284 and a pumping system is employed to distribute the etching fluid from the first mentioned reservoir supply to the two troughs 283 and 284 and this forms an important part of the etching machine assembly inasmuch as it ef-

fects a continuous agitation and mixing of the etching fluid so that the tendency for concentrations of spent or weak etching fluid are not apt to occur.

The pumping system embodies one or more pumps such as those indicated by the reference characters 287 and 288, each having a driving means such as the electric motors 289 and 290. The inlet of each pump is so connected as to pick up the etching fluid from the bottom of the main reservoir or supply chamber within the etching machine, as for example, by means of the inlet pipe 291 shown connected to the pump 288 and being dipped into the etching machine through the opening 292 in the bottom wall 281. The other pump 287 is provided with a similar inlet pipe 293. The outlet of each pump is connected through a valve mechanism suitably accessible to the operator and discharges into one or the other or both of the troughs 283 and 284. For example, the pump 288 is provided with the outlet line 294 which preferably extends up along the side wall 280 to a valve 295 and thence connects with a horizontally disposed distribution line 296 having connections 297 and 298 discharging through the back wall 278 and into the uppermost trough 284, whereas the other pump 287 is provided with a similar discharge or outlet line 299 leading to the valve 300 and thence to the distribution line 301 having the outlet connections 302 and 303 discharging into the lower trough 283.

In etching machines of the general character herein described, it is conventional practice to raise and lower the paddle assemblies 285 and 286 so as to provide a greater or lesser distribution or spray of etching fluid upon the associated plate, the level of etching fluid remaining substantially constant within the reservoir supply beneath or associated with the paddle assembly. However, the present invention contemplates the use of paddle assemblies which, during the normal operation of the machine, are fixed and wherein the pumping system associated therewith in the specific embodiment shown in FIG. 1 and as described above is so controlled as to permit the raising or lowering of the etchant fluid within the troughs 283 and 284 so that the amount of etchant sprayed or distributed by the paddle assemblies is thereby controlled without necessitating any movement of the paddle assemblies themselves.

Furthermore, in the specific embodiment shown, the individual paddles and their troughs with their individual pumping systems permit the individual control of the spray issuing from each paddle assembly. That is, by utilizing a separate pumping system for each paddle assembly, the paddle assemblies may be individually controlled. This is accomplished by means of the valves 295 and 300 which can be manipulated by the operator to preset the flow characteristics in the distribution lines 296 and 301 so as to maintain any desired level of etchant within the troughs 283 and 284, thus individually controlling the spray characteristics delivered by the individual paddle assemblies 285 and 286.

The paddle assemblies themselves are constructed preferably in the manner which is shown most clearly in FIGS. 6 and 7 wherein each will be seen to include a plurality of individual and separate sections 304, 305, 306, etc. Preferably, each of these sections incorporates a centrally disposed hubportion 307 which is hollow so as to receive therethrough a driving axle 308 or 309 as shown in FIG. 1, and with a plurality of blade members 310, 311, 312 and 313 projecting radially therefrom and in equidistantly spaced circumferential relationship as shown most clearly in FIG. 1. The contour of each of the blades is preferably similar to that shown in FIG. 6 wherein there is only a slight concave curvature of the blades as presented to the etchant during normal rotation of the paddle assembly, the rotation being clockwise in FIG. 6. It is important to note, in connection with the contour of the blades, that there is no sharp angularity of the same as would tend to pocket and

trap the etchant as the paddle is rotated, and the curvature is substantially uniform and to such a small degree as to permit the etchant to be thrown from the paddle assemblies in its entirety without any amount of the etchant being retained. This assures a uniform distribution of the etchant as accomplished by the paddle assemblies.

Each of the sections 304, 305, etc. also includes a circular side plate 314 and when all of the sections are mounted upon the associated driving shaft, as is shown in FIG. 7, these side plates 314, 315, 316, etc. abut adjacent blade assemblies, as shown, so as to form a unitary paddle assembly and it is preferred, in this respect, that the individual blades be disposed in alignment with each other along a length of the paddle assembly as is shown in FIG. 7.

The previously mentioned drive shafts 308 and 309 of the paddle assemblies are journaled at opposite ends in the side walls 280 and at the other end thereof project outwardly from the associated side wall and are provided with means such as the pulleys 317 and 318. For the purpose of driving each of the paddle assemblies, there may be mounted on suitable stands or brackets 319 and 320 driving means such as the electric motors 321 and 322 operating through belts 323 and 324 to impart the necessary rotation to the paddle assemblies 385 and 286.

Referring at this time more particularly to FIG. 8, the manner of mounting the opposite ends of the paddle drive shafts will be seen. On the outer side of the associated side wall 280, there is provided a generally L-shaped bracket member 325 presenting a horizontally disposed outwardly projecting upper shelf portion 326 having a pair of dipped holes receiving therethrough the elevating bolts 327 and 328. The bolts 327 and 328 are connected to a pillow block assembly 329 and are rigidly affixed thereto, such pillow block journaling the associated end of the paddle drive shafts, such as the drive shaft 308 as shown. Lock nuts 330 and 331 are associated with the bolts beneath the shelf 326 and when it is desired to make an adjustment of the associated paddle assembly, these lock nuts are backed off as well as the lock nuts 332 and 333 associated with the pillow block assembly and the bolts 327 and 328 are turned to raise or lower the pillow block assembly and, consequently, the associated end of the shaft 308. When the proper adjustment is attained, the lock nuts are, of course, re-tightened to hold the assembly rigid. The purpose of the pillow block adjusting means is to permit the paddle assemblies to be disposed in a direct horizontal position so that they will be uniformly disposed in partial submersions with relation to the etchant solution throughout the lengths of the same so as to cause a uniformity in the spray action imparted thereby across the entire width of the machine. This is necessary, of course, inasmuch as it is easier to adjust the positioning of the paddle assemblies than it is to level the entire etching machine with relation to the paddle assemblies which would otherwise be necessary in order to achieve the proper relationship between the etchant level and the paddle assemblies.

Cooperating with each of the paddle assemblies to provide the desired spray characteristics is a baffle plate, indicated in FIG. 1 by the reference characters 334 and 335, one of such baffle plates being shown in partial detail more clearly in FIG. 9. In the latter figure, the baffle plate 334 will be seen to be provided at its ends with axially projecting journals 336 which project through an arcuated slot 337 in the associated side wall 280 and in turn journalled within a rectangular plate member 338 lying against the outer side of the associated side wall 280. A pair of wing nuts 339 and 340 project through the plate 338 and cooperate therewith and with the arcuate slot 337 to permit the journal end 336 to be located at will at any position within the confines of the slot 337. Since the plate 338 journals the member 336, the baffle plate 334 may be rotated about the longitudinal axis

thereof and suitable means, such as a set screw, not shown, or the like, may be utilized to fix the baffle plate 334 in any desired rotated position with relation to the plate 338. By this construction, the angularity of the baffle plates as well as the fore and aft positioning thereof may be adjusted at will to impart the desired characteristics to the spray issuing from the associated paddle assembly.

FIG. 5 illustrates the construction of the upper portion of the etching machine and illustrates the cover structure therefore as well as a portion of the exhaust ducting therefor. In this figure, it will be seen that the machine is provided with a partially enclosing top wall 341 which projects forwardly from the back wall 278 and terminates substantially midway between the front and back walls as shown. Preferably, the inner end of the fixed top wall portion 341 is provided with a rigidifying bead 342 of suitable configuration to impart sufficient rigidity to this portion of the top to support the overlying slidable cover member 343. The cover member 343 when closed, extends from the inner face of the front wall 279 to a point beyond the inner edge of the fixed top wall portion 341 as shown and is provided thereat preferably with a vertically projecting edge portion 344 serving as a convenient means to grasp the slidable cover and move it backwardly or to the right in FIG. 5 so as to expose the top front portion of the machine to permit the insertion of the magnesium plate and associated support assembly, hereinafter described, into the machine.

For the purpose of exhausting fumes from the interior of the etching machine, the same is provided with one or more exhaust fan structures indicated generally by the reference character 345 in FIG. 5, which are disposed in vertical alignment below outlet portions 346 of an exhaust ducting system. Associated with the fans 345 may be a shroud plate 347 to direct the exhausted fumes toward the central portion of the fan, the fan being preferably of the centrifugal type.

FIG. 1 illustrates the manner in which the fans may be driven and, in this respect, the rear wall 278 of the machine is provided with a pair of brackets 348 and 349 which support electric motors 350 and 351 having drive shafts projecting into the machine and mounting the exhaust fan structure. In this figure also, the exhaust ducting system 352 is more clearly shown.

FIGS. 2 and 3 illustrate the construction of the plate supporting assembly and the manner in which the plate may be manipulated within the machine. In FIG. 2, reference character 353 illustrates a support plate formed of light-weight material, such as aluminum, and having a plurality of uniformly spaced perforations or holes therethrough which are preferably closely spaced so as to render the plate as light as possible. A magnesium printing plate or the like may be fastened to the support plate by a number of suitable screw fasteners which project through the holes provided in plate 353 to hold the printing plate firmly in place. Support plate 353 is provided with a hub 354 having a bore 370 of substantially square cross-sectional configuration formed therein. Square end 355 of support shaft 356 is disposed within bore 370 and is journaled in a suitable bearing block 357 fixed to the inner surface of the front wall 279. A handle mechanism indicated generally by reference character 358 is fixed to the outer end of shaft 356. Hub 354 is also provided with a notch 371 as seen in FIGS. 2 and 3, the divergent side walls 372 and 373 of which flare outwardly from the bore 370. The notch, as seen most clearly in FIG. 2, is not as deep as the bore 370 so that when the support shaft 356 is engaged with the hub 354, the outer end portion of the square end 355 of the support shaft will be firmly sealed within the square socket portion defined by the bore 370 beyond a notch of the hub. The purpose of the notch is to permit the support plate and hub to be easily engaged with the end of support shaft 356 since the divergent walls 372 and

373 of the notch will serve as a guide for the end of shaft 356 as the support plate is moved into engagement therewith until the parts are aligned so that the squared end of the shaft 356 will enter the blind socket portion in the hub.

The handle assembly as shown in FIG. 4, is provided with four radially projecting spokes 359, 360, 361 and 362, the purpose of which will be presently apparent. Fixed to the shaft 356 on the outer side of the front wall 279 is a stop collar member 363 serving to position the shaft 356 in its innermost position. The purpose of the handle assembly, constructed as shown, is to provide an indexing means for the operator in performing the etching operation. That is to say, each etching operation is done on four sides of the printing plate 282 and the spokes provide a convenient index for the operator to produce a quarter of a turn on the support plate assembly 353 and, consequently, the magnesium printing plate 282 attached thereto so as to alternately etch all four sides of the plate 282.

As previously described, the operator may control the spray volume by controlling the valves 295 and 300 and, consequently, the amount of etchant supplied to the troughs 283 and 284, raising or lowering the level therein to increase or diminish the spray volume, as desired. The operator also has access to a series of control switches along the upper side of the machine and as are designated by the reference characters 364, 365, 366, 367 and 368. These controls are, respectively, for operating the fan, for rotating the lower paddle assembly, for rotating the upper paddle assembly, for operating both paddle assemblies simultaneously, and for energizing the two pumps. In addition to these controls, there is a timer mechanism 369 mounted adjacent the controls and preferably including a sweep second hand. By utilizing the controls and operating them in accordance with a prescribed elapsed time, it is possible to eliminate to a large extent, the skill required in the etching operating. In the event that it is desired to etch only certain portions of a plate, the plate should be placed in the machine and only one acid splash paddle assembly is utilized so as to direct the etchant only against those areas of the plate which require etching.

It is apparent from the foregoing that there is provided a new and novel etching machine which minimizes the skill required of an operator to produce proper and uniform results. The apparatus substantially eliminates any tendency for concentrations of weak etching fluid to occur, and the necessity of moving the paddle assemblies to control the amount of etchant sprayed or distributed thereby is eliminated. The paddle assemblies of the device may be individually controlled and they additionally provide a substantially uniform distribution of the etchant. The apparatus is simple and inexpensive in construction, and yet is efficient and reliable in operation.

As this invention may be embodied in several forms without departing from the spirit or essential characteristics thereof, the present embodiment is therefore illustrative and not restrictive, and since the scope of the invention is defined by the appended claims, all changes that fall within the metes and bounds of the claims or that form their functional as well as conjointly cooperative equivalents are therefore intended to be embraced by those claims.

I claim:

1. An etching machine comprising a substantially rectangular tank for containing a supply of etchant, a pair of troughs mounted within said tank in vertically spaced relationship to each other for containing supplies of etchant separate and distinct from the supply contained by said tank, a pump system for circulating etchant from said tank to said troughs, a paddle assembly for each of said troughs and each projecting at least partially into its associated trough to contact the etchant therein, means for driving said paddle assemblies, means for controlling

the flow of etchant effected by said pump means to separately control the etchant level within each individual trough and thus determine the quantity of etchant splashed therefrom by said paddle assemblies, and means for mounting a printing plate within said tank for action thereon by the etchant splashed by said paddle assemblies, said paddle assemblies and said mounting means being so constructed and arranged that etchant sprayed by each of said paddle assemblies is directed toward said mounting means such that the etchant will impinge upon an article supported by the mounting means.

2. An etching machine comprising a tank-like housing providing an etchant reservoir in the lower portion thereof, means for supporting a printing plate in vertical position within said housing, a pair of horizontally disposed, vertically spaced open top troughs fixed within said housing, the lower of which is disposed such that its top is above the level of etchant in said housing, a paddle assembly associated with each of said troughs, each paddle assembly including a plurality of closely spaced blades rotatably supported about a horizontal axis above an associated trough so that the blades pass through the confines of the tank during a portion of their rotary paths, means for rotating said paddle assemblies, means for circulating etchant from the housing reservoir to said troughs whereby to maintain the entire body of etchant in a state of flow, means for controlling the last mentioned means such that a separately variable predetermined etchant level is selectively maintained in each individual trough which is at least as high as the lowermost portion of the paddle assemblies whereby the volume of etchant thrown from the troughs is variable, said paddle assemblies and said support means being so constructed and arranged that etchant sprayed by each of said paddle assemblies is directed toward said support means such that the etchant will impinge upon an article supported by the support means.

3. The assembly as defined in and by claim 2 wherein the printing plate supporting means is manually rotatable to selectively position the plate within the machine.

4. The assembly as defined in and by claim 2 including a deflector plate mounted within said housing above each of said paddle assemblies, each deflector plate being mounted for varying in angle to the horizontal and for moving the same forwardly and rearwardly in said housing so as to selectively position its leading edge disposed closest to the printing plate.

5. An etching machine comprising a substantially rectangular tank for containing a supply of etchant, a pair of troughs mounted within said tank in vertically spaced relationship to each other for containing supplies of etchant separate and distinct from the supply contained by said tank, a pump system for circulating etchant from said tank to said troughs, a paddle assembly for each of said troughs and each projecting at least partially into its associated trough to contact the etchant therein, means for driving said paddle assemblies, means for controlling the flow of etchant effected by said pump means to separately control the etchant level within each individual trough and thus determine the quantity of etchant splashed therefrom by said paddle assemblies, a deflector plate supported within said tank above said paddle assembly for controlling the spray characteristics of the etchant projected from the trough by said paddle assembly, and means for mounting a printing plate within said tank for action thereon by the etchant splashed by said paddle assemblies, said paddle assemblies and said mounting means being so constructed and arranged that etchant sprayed by each of said paddle assemblies is directed toward said mounting means such that the etchant will impinge upon an article supported by the mounting means.

6. An etching machine comprising a substantially rectangular tank for containing a supply of etchant, a pair of troughs mounted within said tank in vertically spaced re-

lationship to each other for containing supplies of etchant separate and distinct from the supply contained by said tank, a pump system for circulating etchant from said tank to said troughs, a paddle assembly for each of said troughs and each projecting at least partially into its associated trough to contact the etchant therein, means for driving said paddle assemblies, means for controlling the flow of etchant effected by said pump means to separately control the etchant level within each individual trough and thus determine the quantity of etchant splashed therefrom by said paddle assemblies, a deflector plate supported within said tank above said paddle assembly for controlling the spray characteristics of the etchant projected from the trough by said paddle assembly, adjustable mounting means for said deflector plate whereby the angularity of the deflector plate with respect to the horizontal may be varied and including means for moving the leading edge of the deflector plate toward and away from a printing plate disposed within the tank, and means for mounting a printing plate within said tank for action thereon by the etchant splashed by said paddle assemblies, said paddle assemblies and said mounting means being so constructed and arranged that etchant sprayed by each of said paddle assemblies is directed toward said mounting means such that the etchant will impinge upon an article supported by the mounting means.

7. An etching machine comprising a housing including an etchant reservoir in the lower portion thereof, means for supporting a printing plate in vertical position within said housing, said supporting means being rotatable to selectively position the plate within the machine, a pair of troughs mounted within said tank in vertically spaced relationship to each other for containing supplies of etchant separate and distinct from the supply contained in said reservoir, a paddle assembly for each of said troughs and each projecting at least partially into its associated trough to contact the etchant therein, means for driving said paddle assemblies, pump means for circulating etchant from the supply within said reservoir to each trough so as to continuously replenish the supply of etchant in each trough and maintain the entire body of etchant in agitated, circulating flow, said pump means including a driven pump having its inlet connected to said tank supply and having a first outlet conduit connected with one of said troughs and a second outlet conduit connected with the other of said troughs, a separate controllable valve connected in each of said conduits for selectively individually controlling the level of etchant in the different troughs to thereby effectively vary the amount of etchant distributed by the paddle assembly of each individual trough, said paddle assemblies and said support means being so constructed and arranged that etchant sprayed by each of said paddle assemblies is directed toward said support means such that the etchant will impinge upon an article supported by the support means.

8. Apparatus as defined in claim 7, including a deflector plate supported within said tank above each of said paddle assemblies for controlling the spray characteristics of the etchant projected from the trough by the associated paddle assembly, each of said deflector plates being separately and individually adjustable whereby the angularity of each deflector plate may be separately varied.
